HEEL WITH EXCHANGEABLE TIP

Heinrich Esser, Berlin-Charlottenburg, Germany

Application January 19, 1939, Serial No. 251,718
In Germany January 22, 1938

3 Claims. (Cl. 36—36)

This invention relates to a heel for footwear with exchangeable tip. Such heels are known, in which the tip fits on a projection provided on the recessed portion of the heel and is held on the heel by the engagement of dove-tailed projections in correspondingly shaped grooves in the heel.

The disadvantage of these known heels with exchangeable tip is that the fixation of the exchangeable tip does not meet the requirements which are essential for practical use. This is due to the fact that, for anchoring the tip, devices are used which are not capable of withstanding the distortions which occur when walking, with the result that the tip can easily become detached. Moreover, these anchoring devices are also partly worn by walking. It must also be pointed out that the production of these heels, owing to their complicated construction are unprofitable for the manufacturers and their use for the consumer is impractical.

All these objections are avoided by the invention in that the projection provided on the recessed portion of the heel forms with the opposite oblique face of the heel a continuous groove for the purpose of anchorage.

Other features of the invention will become apparent from the following description.

Two embodiments of the invention are illustrated by way of example in the accompanying drawing, in which:

Fig. 1 shows in bottom plan view a heel with exchangeable tip.

Fig. 2 is a similar view to Fig. 1 showing the heel with the tip removed.

Fig. 3 is a section on line A—B of Fig. 2.

Fig. 4 shows the heel in rear elevation.

Fig. 5 shows a modified form of construction in section on line C—D of Fig. 2.

The heel is designated by 1 and the tip by 2. For the purpose of exchangeability the tip is anchored on the heel in that the heel body has a plate-shaped projection 3 whose shape corresponds to that of a recess in the under side of the tip. The dimensional proportions between the plate-shaped projection 3 and the recess in the tip are chosen so that, if the tip is made of elastic material, it is stretched over the projection 3 and thus secured against horizontal movement. For securing the tip against vertical movement the straight edge of the tip is undercut at a sharp angle and this undercut edge engages under a counter bevel on the rear abutting edge of the heel body as shown in Fig. 3. The distance between the inner edge *a* of the plate-

shaped projection and the opposite point *c* of the abutting edge of the heel body is smaller than the width at the bottom *d* of the groove. The bearing edge of the tip 2 and the bearing edge on the heel 1 are cut to fit one another. For 5 securing the tip in position a projection 4 is formed at the curved edge of the tip, for example in the shape of a dove-tail, and engages in a correspondingly shaped recess in the heel.

The foregoing shows that it is now possible, 10 when the tip is of elastic material, to press by hand the straight edge of the tip into the gap between the plate-shaped projection and the abutting edge of the heel, to stretch the tip over the plate-shaped projection 3 and finally to press the 15 projection 4 into the corresponding recess in the heel.

The removal of the tip is effected in inverse manner, that is the projection 4 is pulled out of the recess, the tip pulled off the plate-shaped 20 projection 3 and out of the gap between the projection 3 and abutting edge of the heel.

As can be seen from Fig. 5, especially the right half thereof, the bottom surface of the cut away portion of the edge of the heel body for accommodating the tip, if this is made of elastic material, slopes downwards towards the middle of the heel as shown at *d*. The lower edge of the tip is correspondingly bevelled. Thus, the tip is pressed strongly on to the heel body when 30 walking.

The tip may be made without projection 4. In this instance the curved edge of the plate-shaped projection is partly or entirely under-cut and the edge of the recess bevelled to conform to the 35 under side of the tip.

According to a modified form of construction the heel body is composed of two parts instead of being made in one piece. In this instance the top lift 5 is removably fixed on the heel body. 40 The fixation may be effected by nails, locking elements or screws. The removable top lift 5 is provided on its under side with pins 6 which engage in corresponding recesses in the heel body, so that the top lift always assumes and retains 45 the same position. This form of construction is necessary, when the exchangeable tip is made of non-elastic material, for example metal. The tip can then be exchanged as soon as the top lift 5 has been removed. The remaining parts are 50 constructed as above described, but with the difference that the two abutting surfaces, one on the edge of the heel body and the other on the tip, are at right angles.

I claim:

1. A heel with exchangeable tip, comprising in combination a heel body having a recessed portion at its rear end, a straight undercut edge bordering said recessed portion, a projection at the bottom of said recessed portion having a straight edge opposite said straight bevelled edge and forming therewith a continuous groove, the tip having in its under side a recess corresponding to the shape of said projection bordered by an edge conforming to the cross-sectional shape of said groove.
- 5 2. A heel was specified in claim 1, in which the groove widens towards the bottom and the heel body has a dove-tailed recess in the rounded edge of its recessed portion at the point farthest remote from the bevelled edge, a dove-tailed projection being formed on the under side of the
- 10 15

tip to fit in said dove-tailed recess to anchor said tip in position on said heel body.

3. A heel as specified in claim 1, in which the groove widens towards the bottom and the heel body has a dove-tailed recess in the rounded edge 5 of its recessed portion at the point farthest remote from the bevelled edge, a dove-tailed projection being formed on the under side of the tip to fit in said dove-tailed recess to anchor said tip in position on said heel body, the bottom of 10 said dove-tailed recess being downwardly inclined from the rounded edge towards the centre of the heel body, and the lower surface of the dove-tailed projection on the tip having a slope corresponding to the incline of the bottom of the 15 dove-tailed recess.

HEINRICH ESSER.
